TEETER MOTOR GAME

William M. Gates, Montrose, Colo.

Application October 15, 1945, Serial No. 622,247

3 Claims. (Cl. 46—43)

This invention relates to a teeter-motor and more particularly to a mechanical toy for children which is actuated by marbles or other rolling elements.

An object of this invention is to provide a toy that is simple, inexpensive to manufacture and will afford children a great deal of pleasure.

With the foregoing and other objects in view which will appear as the description proceeds the invention resides in the combination and arrangement of parts and in the details of construction hereinafter described and claimed, it being understood that changes in the precise embodiment of the invention herein described may be made within the scope of what is claimed without departing from the spirit of the invention.

Referring to the drawings:

Figure 1 is a top plan view of a toy embodying the invention.

Figure 2 is a side view thereof partly broken away.

Figure 3 is an end view thereof partly in section and partly broken away and

Figure 4 is a sectional view on the line 4—4 of Figure 2.

Referring to the drawings in detail the reference character 10 designates the frame of the toy which comprises vertical inclined legs 12 and 14 respectively connected in oppositely positioned pairs by horizontal braces 16.

The legs 12 are of a greater height than the legs 14 and the legs support the trough or gravity runway 18 at an incline.

The highest end of the runway 18 is provided with a hopper 20, having an inclined floor 22 which is adapted to hold the marbles or other rolling elements 24 therein.

Immediately adjacent the hopper 20 and communicating therewith is the rotor housing 26 for the rotor 28, which is mounted on the shaft 30 journalled in the sides of the housing 26.

The rotor 28 is provided with the depression 32 of a slightly larger size than the marbles 24, and when fed from the hopper 20 the marbles will enter the depression 32.

When the rotor 28 revolves it will convey the marbles to the lower end of the trough 18 and traveling downward the marbles will drop through the opening 34 in the end thereof. The marbles will then drop into the cup 36 fastened on the end of the teeter totter 38 which is pivoted at 40 by means of the shaft 42, journalled in bearings 44, secured to the braces 16 will be overbalanced and permit the marbles 24 to be

deposited into the inclined return chute 46 down which the marbles will roll to be collected at the end thereof. The shaft 42 is secured to the teeter totter 38 by means of the bearings 44.

5 The movement of the teeter totter 38 will actuate the link 48, which is pivotally connected to the teeter totter by a pin 50 journalled in bearings 52, fixed to the teeter totter. The link 48 will actuate the rotor 28 by means of a link 54 pivoted thereto at 56 and secured to the rotor shaft 30 at 58. Thus the rotor will be actuated to cause the marbles 24 to roll down the trough 18.

15 The movement of the teeter totter 38 will also 15 revolve the flywheel or belt pulley 60 by means of the following mechanism.

The pulley 60 is mounted on the crank shaft 62 which is journalled in bearings 64 mounted on the braces 16 and a link 66 mounted on the 20 shaft 62 is pivotally connected to the teeter totter 38 by means of a pin 68 secured to the teeter totter 38 by L-shaped bearings 70.

25 The teeter totter 38 is provided with a counter weight 72 at the end thereof and the return chute 48 is provided with the extended sides 74 at the point where the marbles 24 are deposited therein.

30 In operation of the toy the teeter totter 38, will be moved to permit a marble to roll down the trough 18 or a marble can be dropped into the trough 18 by hand the actuation of the teeter totter by the weight of the marble falling thereon will actuate the rotor to feed another marble into the trough at the same time revolving the 35 wheel 60, this will continue until all the marbles have been discharged from the hopper or if the child desires he can collect the marbles at the lower end of the return chute and continue the toy in operation as long as he continues to feed 40 the marbles to the hopper.

It is believed that the operation and construction of the toy will be apparent to those skilled in the art and it will be seen that a toy has been provided that will accomplish the objects of the 45 invention.

Having thus described the invention what is claimed as new and desired to be secured by Letters Patent is:

50 1. A device of the character described comprising a frame adapted to support a gravity runway, a hopper at the upper end of said runway, a housing communicating with said hopper, a rotor having a depression therein communicating with said hopper, a cup positioned below 55 the lower end of said runway a teeter totter sup-

porting said cup and means connected to said teeter totter for actuating said rotor to convey marbles contained in said hopper to said runway.

2. The invention as in claim 1 wherein a wheel mounted on a crank shaft is adapted to be rotated by means connecting said crank shaft to said teeter totter.

3. The invention as in claim 1 wherein the upper end of a gravity return chute is positioned below said cup to receive marbles deposited therein from said cup.

WILLIAM M. GATES.
